US00D925437S

(12) **United States Design Patent** (10) **Patent No.:** **US D925,437 S**
(45) **Date of Patent:** **** Jul. 20, 2021**

(54) **TIRE TREAD**

(71) **Applicant:** **Kenda Rubber Industrial Co., Ltd.**,
Yuanlin (TW)

(72) **Inventors:** **Jouni Juhani Raatikainen**, Lempäälä
(FI); **Mikko Valtteri Sironen**, Tampere
(FI)

(73) **Assignee:** **KENDA RUBBER INDUSTRIAL
CO., LTD.**, Yuanlin (TW)

(**) **Term:** **15 Years**

(21) **Appl. No.:** **29/723,091**

(22) **Filed:** **Feb. 4, 2020**

(30) **Foreign Application Priority Data**

Sep. 20, 2019 (EM) 006892733-001

(51) **LOC (13) Cl.** **12-15**

(52) **U.S. Cl.**

USPC **D12/521**

Design U.S. Appl. No. 29/530,655, filed Jun. 18, 2015, entitled Tire Tread, Inventors: Raatikainen et al.

(Continued)

Primary Examiner — John A Voytek

(74) *Attorney, Agent, or Firm* — Thompson Hine LLP

(57) **CLAIM**

The ornamental design for tire tread, as shown and described.

DESCRIPTION

FIG. 1 is a perspective view of the design;

FIG. 2 is a front view of the design of FIG. 1;

FIG. 3 is a side view of a first side of the design of FIG. 1; FIG. 4 is a side view of a second side of the design of FIG. 1; and,

FIG. 5 is a detail view of a portion of FIG. 2.

In the drawings, the broken lines depict environmental subject matter only and form no part of the claimed design. Attachment A includes a set of drawings showing additional details relating to the design shown in FIGS. 1-5, but the content of Attachment A forms no part of the claimed design.

1 Claim, 5 Drawing Sheets
